UNITED STATES PATENT OFFICE.

SARAH M. BEVERLY, OF ROCHESTER, INDIANA, BY MARRIAGE NOW SARAH M. BEVERLY MILLARD.

AUXILIARY SEAT FOR VEHICLES.

SPECIFICATION forming part of Letters Patent No. 336,785, dated February 23, 1886.

Application filed July 23, 1885. Serial No. 152,394. (No model.)

To all whom it may concern:

Be it known that I, SARAH M. BEVERLY, of Rochester, Fulton county, Indiana, have invented certain new and useful Improvements in Auxiliary Seats for Vehicles, of which the following is a specification, reference being had to the accompanying drawings, forming part hereof, in which—

Figure 1 is a perspective view of a vehicle-seat having my auxiliary seat mounted thereon, the cushion of my auxiliary seat and one of the cushions of the vehicle-seat being removed. Fig. 2 is a central transverse section through the vehicle-seat and my auxiliary seat, the auxiliary seat being in its inactive or stored position. Fig. 3 is a perspective view of the spring-bar which supports my auxiliary seat. Fig. 4 is a perspective view of the slideway in which my auxiliary seat is secured; and Fig. 5 is a top plan view of the central portion of the vehicle-seat, part of the slideway being broken away.

Like letters of reference mark the same parts in all the figures.

My invention relates to auxiliary seats for vehicles; and it consists in the improved construction, arrangement, and combination of parts, which I shall now proceed to fully describe, and afterward point out specifically in the claims.

Referring to the drawings by letter, A is an ordinary vehicle-seat designed to accommodate two persons, having sides A' and back A'.

B is one of the two cushions ordinarily used. C is a metal or wood slideway, which is so shaped as to form an opening, c, when secured to the seat A by screws, nails, or other fastenings through the holes c'.

D is a spring-bar upon which my auxiliary seat is secured, and which serves to support it in both the upper and lower positions, as shown in Figs. 1 and 2. This spring-bar D has a horizontal portion, d, provided with holes, by means of which the auxiliary seat is secured

45 by screws, bolts, or rivets e, as shown in Fig. 2. It has also a vertical portion, d', a curved portion, d'', and a horizontal portion, d'', terminating in a rounded portion, d'''.

E is my auxiliary seat, which may be of any 50 desired form or construction.

d'' is a small semi-cylindrical groove cut in the forward side of the seat A, having stop or shoulder d'', as shown, which serves a purpose hereinafter stated.

The slideway C being secured to seat A and 55 the auxiliary seat to spring-arm D, my device is ready to be operative by placing the horizontal portion d'' in the slideway, with the seat in the position shown in Fig. 1. In this position it is ready for occupancy by a third person, both sides of the main seat being occupied by a person, as usual. When it is no longer desired for use, the spring-bar is drawn forward until the rounded end d''' drops into groove d'', when the spring-arm and seat may 60 be turned on the end d'' as an axis, bringing the auxiliary seat to the position shown in Fig. 2, being entirely under the seat A and out of the way. The lug or stop d'' prevents the accidental removal of the bar, the head on the 65 part d''' engaging said lug.

The advantages of the construction shown are many. The auxiliary seat is directly over the main seat, so that the occupant thereof is not crowded against the dash-board, being at 75 the same time sufficiently raised above the main seat to be out of the way of the occupants of the main seat. It has a spring-support independent of the vehicle-spring, and when no longer desired for use may be put into the position seen in Fig. 2, entirely under the seat out of the way, and to do this no removing of screws or other fastenings is necessary; nor need the spring-bar be entirely removed from the slide-way. If desired, however, the auxiliary seat 85 and spring-bar may be entirely removed from the vehicle and stored away at will.

The spring-bar and other described parts may be varied to suit varying circumstances in size and material without departing from 90 the spirit of my invention.

Having thus fully described my invention, I claim as new and desire to secure by Letters Patent of the United States—

1. An auxiliary seat for vehicles, provided 95 with a spring supporting-bar having a horizontal portion, d, upon which the seat is secured, a curved portion, and a horizontal portion, d'', rounded at d'', whereby the seat is firmly supported in or turned to either its up- 100

per (or active) or lower (or inactive) positions, as shown.

2. The auxiliary seat E, having spring-support D, composed of horizontal portion d , upright portion d' , curved portion d'' , and horizontal portion d^3 , ending in rounded portion d^4 , as set forth.

3. An auxiliary seat for vehicles, mounted on a spring-support having a horizontal end, d^5 , in combination with the ordinary seat, provided with a slideway in which said end fits in either its upright or reversed positions, whereby the seat is firmly supported in either of these positions, as set forth.

4. The seat A, having slideway C and groove d^6 , with lug d^7 , in combination with spring-support D, having horizontal portion d^8 , with rounded end d^9 , and the auxiliary seat, as set forth.

In testimony whereof I have signed my name 20 in presence of two witnesses.

SARAH M. BEVERLY.
